UNITED STATES PATENT OFFICE.

BENJAMIN WOLHAUPTER, OF CHICAGO, ILLINOIS.

TIE-PLATE.

No. 832,946.

Specification of Letters Patent.

Patented Oct. 9, 1906.

Application filed June 26, 1905. Serial No. 266,992.

To all whom it may concern:

Be it known that I, BENJAMIN WOLHAUPTER, a citizen of the United States, and a resident of Chicago, in the county of Cook and State of Illinois, have invented certain new and useful Improvements in Tie-Plates; and I do hereby declare that the following is a full, clear, and exact description thereof, reference being had to the accompanying drawings, and to the letters of reference marked thereon, which form a part of this specification.

This invention relates to a novel railway tie-plate or plates adapted to rest upon wooden railway-ties beneath the rails and to be used in connection with shouldered lag-screws or screw-spikes in cases where such screws are employed to secure the rails to the ties.

20 The invention consists in the matters hereinafter described, and set forth in the appended claims.

In the accompanying drawings, illustrating my invention, Figure 1 is a sectional view taken upon line 1-1 of Fig. 2 of a track-rail and tie, together with a tie-plate made in accordance with my invention. Fig. 2 is a plan view of the rail and tie-plate shown in Fig. 1. Fig. 3 is a detail section taken 25 through the margin of the rail-flange at the end of the tie-plate and adjacent part of the tie, showing a modified form of construction of the tie-plate embodying my invention. Fig. 4 is a plan view of the construction 30 shown in Fig. 3. Figs. 5 and 6 are views corresponding with Figs. 3 and 4, showing still another modification in the construction of the tie-plate. Figs. 7 and 8 are still other views corresponding with Figs. 3 and 4 and 35 showing still another modification in the construction of the tie-plate.

As shown in said drawings, A indicates the track-rail, and *a a* the base-flanges thereof.

B indicates the wooden tie on which the 45 rail is supported, C the tie-plate, and D D D the lag-screws or screw-spikes by which the rail is attached to the tie. Each of the screw-spikes D is of common form, having at its upper end an annular flange or head *d*, and 50 above said flange a squared or flat-sided projection *d'* for the application of a wrench by which the screw-spike is turned in inserting it into the tie. The flange or head *d* forms

an annular downwardly-facing shoulder which overlaps and bears against the marginal part of the base-flange *a* of the rail. 55

The tie-plate C is made generally in a manner heretofore common—that is to say, it has in general the form of a flat plate with a horizontal top surface forming the rail-seat 60 and provided near one of its ends or at one side of the rail-seat with an elevated rib *c*, extending parallel with the rail and shaped to form an inwardly-facing shoulder against which rests the edge of the base-flange of the 65 rail. The tie-plate provided with a flange *c*, as described, is placed beneath the rail with the flange in contact with the outer side of the rail, so that the flange serves to resist the tendency to outward movement in the rail 70 due to the pressure of the flanges of the car-wheels on the inner side of the rail-head. Said tie-plate C is provided with holes for the screw-spikes, one of which is shown at the left side of Fig. 1 and there indicated by *c'*. 75 The tie-plate is shown as provided with holes for three screw-spikes, two of which latter are located at the outer side of the rail and one at the inner side thereof.

Now referring to the novel feature in the 80 tie-plate to which my invention more particularly relates, said tie-plate, as shown in Figs. 1 and 2, is provided near its end margins and outside of the holes through which the lag-screws are inserted with elevated ribs 85 or upwardly-projecting flanges *C' C²*, the ribs *C' C²* being located outside of and parallel with the bearing-ribs *c*. The top surfaces of the ribs *C' C²* are located approximately in the same horizontal plane with the top surfaces of the outer margins of the base-flanges *a a* of the rail, and in such position with respect to the spike-holes in the tie-plate that when the screw-spikes are inserted into the ties through said holes with their heads or 95 flanges *d* in bearing contact with the rail-flanges, said heads or flanges will bear at their outer parts upon the top surfaces of the said ribs *C' C²*.

The advantage gained by the presence of the ribs *C' C²* on the tie-plate is that the outer parts of the heads or flanges of the screw-spikes are, when said spikes are tightened against the base-flanges of the rail, held up or supported by their contact with the bearing-shoulders 100 formed by said ribs *C' C²* and are thereby 105

rigidly retained in an upright position and held from tipping or tilting outwardly at their upper ends, as is liable to occur when the heads of the spikes bear upon the rail-flanges only. Moreover, in the absence of the bearing-shoulders on the tie-plates the tightening of the spike-heads against the base-flanges of the rail in itself would tend to tip or tilt the spikes in the tie in such manner as to throw the upper ends of the spikes outwardly or away from the rail, but when the said shoulders are present the spike-head has equal bearing at its inner part on the base-flange of the rail and at its outer part on the bearing-surface, so that the spike retains its upright position when inserted and tightened and is held from assuming an outwardly-inclined position under outward pressure of the rail or tie-plate thereon.

20 The ribs or flanges C' C² are shown in Figs. 1 and 2 as extending across the full width of the tie-plate; but this construction is not essential and is used on the tie-plate illustrated for convenience of manufacture in case of tie-plates produced from a rolled blank, a long blank from which a number of tie-plates are to be made being rolled to the cross-sectional shape shown in Fig. 1 and pieces of suitable length to form the individual tie-plates being 25 then cut from the long blank in the manner common in the manufacture of tie-plates from rolled blanks.

20 The ribs or flanges C' C² are shown in Figs. 1 and 2 as extending across the full width of the tie-plate; but this construction is not essential and is used on the tie-plate illustrated for convenience of manufacture in case of tie-plates produced from a rolled blank, a long blank from which a number of tie-plates are to be made being rolled to the cross-sectional shape shown in Fig. 1 and pieces of suitable length to form the individual tie-plates being 25 then cut from the long blank in the manner common in the manufacture of tie-plates from rolled blanks.

In Figs. 3, 4, 5, and 6 I have shown modified constructions in wrought metal or rolled tie-plates wherein an elevation on the tie-plate forming a supporting-shoulder located in position to engage the head of the screw-spikes at the side thereof opposite that which engages the base-flange of the rail is provided 30 by means of an integral upwardly-bent portion of the tie-plate itself. As shown in Figs. 3 and 4, the tie-plate is provided outside of the hole c' for the screw-spikes with two transverse cuts or slits forming a tongue C³, which 35 is bent upwardly or into a vertical position and the upper end of which is disposed in the same horizontal plane with the marginal part of the base-flange of the rail. The tongue C³ thus arranged forms a bearing-shoulder adapted to perform the same function as the like bearing-shoulder formed by the rib C' or C². (Shown in Fig. 1.) In Fig. 45 5 and 6 I have shown still another modification wherein the tie-plate C is provided with a tongue or projection C⁴, formed by the metal cut out in forming the spike-holes c and bent upwardly into vertical position so that its top surface is in the same horizontal plane with the top surface of the adjacent 50 margin of the base-flange of the rail and is so located as to come beneath the external part of the screw-spikes head, as clearly shown in Fig. 5.

The general features of construction here-

inbefore referred to may be applied as well to 65 a cast-metal tie-plate, and in Figs. 7 and 8 I have shown a construction wherein the tie-plate is provided with an elevated part C⁵, located exterior to the spike-hole and extending around the outer part of the said hole. 70 The top of the elevation C⁵ is made of proper height for contact with the under surface or shoulder of the spike-head when the latter comes in bearing against the base-flange of the rail, with the same results as hereinbefore set forth. 75

The downwardly-facing shoulder formed by the head or flange d of the screw-spikes is shown as made of conical form and inclined to correspond with the inclination of the top 80 surface of the base-flange of the rail. When the said under surface of the spike-head is thus made of conical form, the bearing-shoulders formed by the top surfaces of the supporting-ribs, lugs, or elevations on the tie-plate will be correspondingly beveled or inclined, as clearly shown in the several figures of the drawings, so that when the head of the screw-spikes is tightened against the rail it will come to a firm and solid bearing on said 90 rib, lug, or elevation.

I claim as my invention—

1. A tie-plate provided at one side of the rail-seat with a rib forming an inwardly-facing bearing-shoulder for contact with the 95 base-flange of the rail, with a hole for a screw-spikes, and with an elevated bearing outside of the spike-hole and separate from said bearing-shoulder, adapted for contact with the head or flange of the screw-spikes. 100

2. A tie-plate provided at one side of the rail-seat with a rib forming an inwardly-facing bearing-shoulder for contact with the base-flange of the rail, with a hole for a screw-spikes, and with an elevated bearing 105 outside of the spike-hole and separate from said bearing-shoulder adapted for contact with the head or flange of the screw-spikes, the under surface of the spike-head being inclined to correspond with the inclination of the top surface of the base-flange of the rail, and the upper surface of said elevated bearing being likewise inclined to correspond with the under surface of said head. 110

3. A tie-plate provided with holes for 115 screw-spikes located outside of the rail-seat and provided outside of said holes with raised bearings adapted for contact with the heads or flanges of the screw-spikes, said raised bearings being provided with enlarged 120 curved bearing-surfaces for contact with said heads.

4. A tie-plate provided at one side of the rail-seat with a rib forming an inwardly-facing bearing-shoulder for contact with the 125 base-flange of the rail, with a hole for a screw-spikes and with an elevated bearing outside of and separate from said bearing-

shoulder adapted for contact with the head of the flange of the screw-spike, said elevated bearing being inclined to correspond with the base-flange of the rail and provided with an
5 enlarged curved bearing-surface which partially surrounds the spike-hole adapted for engagement with the under inclined side of the spike-head.

In testimony that I claim the foregoing as my invention I affix my signature, in presence of two witnesses, this 21st day of June, A. D. 1905.

BENJAMIN WOLHAUPTER.
